UNITED STATES PATENT OFFICE.

JOSEPH BERGER, OF BAYONNE, NEW JERSEY, ASSIGNOR TO THE SINGER MANUFACTURING COMPANY, A CORPORATION OF NEW JERSEY.

SEWING-MACHINE.

1,133,608.

Specification of Letters Patent. Patented Mar. 30, 1915.

Application filed November 2, 1910. Serial No. 590,270.

To all whom it may concern:

Be it known that I, JOSEPH BERGER, a citizen of the United States, residing at Bayonne, in the county of Hudson and State 5 of New Jersey, have invented certain new and useful Improvements in Sewing-Machines, of which the following is a specification, reference being had therein to the accompanying drawings.

10 This invention has for its primary object to provide a seam covering machine for producing a covering seam presenting upon the under side two parallel rows of stitches and upon the upper side cross stitches formed by 15 the covering thread uniting said parallel rows of stitches.

In accordance with the present improvement, in its preferred form, the machine is constructed with a frame comprising a bed 20 and an overhanging bracket-arm, the main-shaft being disposed longitudinally of the bed and parallel, looper-supporting, and actuating rock-shafts being journaled in the bracket-arm and operatively connected with 25 the main-shaft. Journaled for vertical reciprocation in the bed is a needle-bar operatively connected with the main-shaft and carrying a plurality of needles disposed in longitudinal arrangement and adapted for 30 co-operation with a single loop-taker, preferably in the form of an eyed looper, mounted upon a carrier having a transverse fulcrum upon the looper-supporting rock-shaft and a crank-and-pitman connection with the 35 looper-actuating rock-shaft.

As the looper is necessarily disposed at some distance above the top of the throat-plate, means connected with the needle-bar actuating mechanism are provided for reducing the size of the loops thrown out by 40 the needles so as to insure the normal co-action of the looper with the needles for preventing the liability to skipping of 45 stitches which would result from the described relation of the needles and looper relative to the throat-plate. The needle-bar carries a thread-arm formed with thread-eyes through which the needle-threads pass to the needles from a pair of adjacent fixed 50 thread-eyes intermediate the same and the needle-thread tension devices by means of which the needle-threads are drawn up to set the preceding stitches as the needle-bar moves upwardly in each stitch-forming 55 cycle.

Fixed upon the looper-supporting rock-shaft is a pair of spaced parallel cam-plates operating in conjunction with a pair of spaced arms mounted upon the looper-carrier and embracing said cam-plates in such 60 manner as to lead the looper-thread across the cam-shaped edges of the cam-plates for controlling the slack of the looper-thread. The looper-supporting rock-shaft is further provided with a nipper-arm adapted to co-operate with a looper-thread nipping member fixed upon the bracket-arm, between which and the looper-thread tension is arranged an arched thread-guide formed with 65 alined thread holes between which vibrates 70 a pull-off arm fixed upon the looper-actuating rock-shaft.

In the accompanying drawings, Figure 1 is a front side elevation, partly in section, representing a sewing machine constructed 75 in accordance with the present invention, Fig. 2 a front end elevation of the same with the work-plate in section and the face-plate of the bracket-arm removed, and Fig. 3 a transverse section through the upright portion of the bracket-arm and the base of the frame. Fig. 4 is a perspective view representing the needle-thread take-up and loop-reducing devices. Figs. 5 and 6 are perspective views, the latter partly in section, showing a form of presser-foot which is 80 preferably used in the machine. Fig. 7 is a perspective view representing the looper and the looper-thread take-up and nipping devices, and Fig. 8 a similar view, upon a 85 larger scale, of the looper-carrier. Fig. 9 is a perspective view of the forward portion of the looper-supporting rock-shaft affording the bearing for the looper-carrier 90 fulcrum-pin.

As represented in the drawings, the frame of the machine is constructed with the base 1 integral with which is formed the hollow upright portion 2 of the bracket-arm formed with the tubular overhanging part 3 terminating in the hollow head 4 provided with the face-plate 5. Journaled within and longitudinally of the base is the main-shaft 6 carrying at its forward end the crank-plate 7 with crank-pin 8 embraced by one end of 105 the pitman 9 whose opposite end embraces the crank-pin 10 of a collar 11 fixed upon the needle-bar 12 journaled in the vertical bearing bushings 13 of the brackets 14 with 110 which the base 1 is provided. The needle-

bar is provided at its upper end with the twin-needle clamp 15 carrying the needles 16 disposed in a vertical plane parallel with the main-shaft.

5   Mounted in suitable bearings 17 within and arranged longitudinally of the hollow overhanging member 3 of the bracket-arm is disposed the looper-actuating rock-shaft 18 having fixed upon its rearward end a 10 collar 19 with a lateral crank-arm 20 provided with the pin 21 embraced by the upper end of the pitman-rod 22 whose opposite end embraces a crank 23 formed in the rearward portion of the main-shaft. Mounted 15 in suitable bearings 24 and 25 in the bracket-arm head 4 and upright portion 2 is the looper-supporting rock-shaft 26 arranged parallel with the main-shaft and with the rock-shaft 18 and having fixed upon its rearward end the hub 27 of a depending arm 28 20 provided at its lower end with a split fork 29 which embraces an actuating eccentric 30 of the main-shaft adjacent the crank 23. The forward end of the looper-supporting 25 rock-shaft 26 is formed with a flattened head 31 having a depending portion provided with a transverse aperture 32 and is formed with a forwardly projecting flange 33 with screw-apertures 34 the object of 30 which will be later described. Mounted within the aperture 32 of the rock-shaft head 31 is the fulcrum-pin 35 which enters the alined apertures 36 of the spaced members 37* of the looper-carrier 37 which embrace the rock-shaft head 31. The looper-carrier is formed with a depending lug 38 35 provided in one face with recesses 39 and 40 to afford seats for a member of the take-up and the shank of the looper respectively.

40   The looper herein shown is of the double chain-stitch type and comprises a blade 41 having a thread-eye 42 near its point with adjacent thread-groove 43 in one side leading to a second thread-eye 44 in the heel, 45 and has the usual shank 45 in angular arrangement with the blade and provided with a transverse butt end 46 secured within the seat 40 of the looper-carrier by means of the fastening screw 47 entering a threaded 50 aperture 48 in the latter. To the shank of the looper is secured by means of the fastening screw 49 the shank 50 of the looper-guard whose blade 51 extends somewhat in advance of the looper point and is maintained spaced therefrom to afford a space 55 for passage of the needles by means of the adjusting screw 52 whose reduced extremity, which enters an aperture in the looper-guard, cooperates with the fastening screw 50 59 in maintaining the looper-guard in overlying relation with the looper-blade.

60   The looper-carrier is formed with a lateral arm 53 having an eye 54 in which is secured a ball-stud 55 embraced by a strap 65 56 upon the lower end of a pitman-rod 57

whose upper end is provided with a strap 58 which embraces a ball-stud 59 upon a lateral crank-arm 60 fixed upon the forward end of the looper-actuating rock-shaft 18. As will be readily understood, the rock-shaft 70 18 operates through the connections just described to oscillate the looper-carrier upon its fulcrum-pin 35 to impart endwise or loop-seizing and shedding movements to the looper, while the oscillation of the looper-carrier rock-shaft 26 serves to impart to the looper-carrier and thus to the looper, its sidewise or needle-avoiding movements. 75

Extending forwardly from the needle-clamp is a rigid thread-arm 61 whose upturned end portion 62 has a pair of vertically arranged thread-eyes 63; and fixed upon the casing 64 beneath the work-plate 65, by means of the fastening screw 66 passing through its foot 67 is a guide-arm 68 80 provided with the thread-eyes 69 through which the needle-threads are led from the tension devices 70 and 71 to the eyes 63 of the thread-arm 61 from which they are led through the apertures 72 formed in a guide-flange 73 of the needle-clamp to the eyes of the needles. The casing 64 is provided intermediate the guide-member 68 and thread-arm 61 with a guide-finger 74 having a foot-piece 75 formed with a slot 76 entered by a fastening screw 77 by means of which it is adjustably secured in place. 90

Journalized upon the needle-bar actuating crank-pin 8 by means of the aperture 78 at the junction of its arms is an elbow-lever 100 formed with an upwardly curved lateral thread-engaging arm 79 and a depending arm 80 formed with a transverse slot 81 entered by a fastening screw 82 by means of which it is adjustably secured upon the pitman. By loosening the fastening screw 81 the thread-engaging arm 79 may be shifted into different angular relations with the pitman 9. 105

As will be seen by reference more particularly to Fig. 4, the needle-thread *a* is led from the tension device 70 through the outer thread-eye 69 of the guide-member 68 beneath the thread-finger 74 over the thread-arm 79, through the lower eye 63 of the arm 61 and thence through one of the eyes 72 to the eye of the inner and longer needle 16. The thread *b* is similarly led from the tension 71 through the inner thread-eye 69 beneath the finger 74, over the thread-arm 79, through the upper guide-eye 63 and thence through one of the needle-clamp eyes 72 to the eye of the outer and shorter needle 16. 115 As the crank-pin 8 revolves and imparts the reciprocatory movements to the needles 120 the throat-plate 83, the rigid thread-arm 61 rises with the needle-bar and bends the needle-threads leading to its eye 63 from the guide-member 68 beneath the thread-finger 74, thereby drawing up the needle-threads to 125 130

set the preceding stitches. In the continued rotation of the crank-pin 8 thereafter, the thread-arm 79 is carried bodily outwardly and upwardly and then inwardly toward the 5 threads, engaging first the needle-thread *a* of the inner and longer needle, and then the thread *b* of the shorter needle, so as to draw in different amounts of slack just as the needles begin their descent to throw out their 10 thread-loops, the slack thus drawn in being just sufficient to reduce the loops to normal size for entrance of the looper so as to avoid kinking or deflection around the needle-blades and thus preventing the missing of 15 the needle-thread loops by the looper-point.

The needle-thread drawing means connected with and actuated by the needle mechanism therefor acts upon the needle-thread first at the end of the advance movement of 20 the needles through the material and again while the needles are still in the material and preparatory to presentation of their thread-loops for seizure by the loop-taker.

Secured by the fastening screws 84 upon 25 and spaced apart by means of the flange 33 of the rock-shaft head 31 are the parallel cam-plates 85 each formed with curved outer or forward edge 86 terminating near the bottom in a peripheral notch 87. Secured in 30 suitable radial sockets 88 of the looper-carrier members 37* are the thread-guide rods 89 embracing and spaced from the cam-plates 85 and each provided with a thread-eye 90 within the cam-shaped periphery of 35 the adjacent plate 85. Secured upon the transverse seat 39 of the looper-carrier lug 38 by means of the screw 91 is the shank 92 of a cast-off member 93 having at its outer end an angularly disposed thread-engaging 40 finger 94 adapted for movement in unison with the rods 89 upon the looper-carrier but intermediate the cam-plates 85 and slightly in advance of the members 89 in their downward movement.

45 The looper-thread *c* is led from the source of supply through an eye 95 of a bracket-piece 96 secured by means of a screw 97 upon the forward cam-plate 85, thence through the eye of one of the vibratory rods 50 89, around the operative edges of the cam-plates 85 through the eye of the other rod 89, and thence downwardly through the eye in the heel of the looper to the looper-point.

In the operation of the machine, when the 55 looper is retracted, the thread-eyes 95 and 90 are in substantial alinement, and the looper-thread passes freely through the take-up device. As the looper advances to seize the needle-thread loops, the slack thus 60 formed between the looper-point and the work is gradually taken up by the action of the cam-plates intermediate the eyes of the vibratory rods 89, but thread from the source of supply is permitted to pass freely 65 through the take-up device to supply the

thread leading from the material to the advanced looper-point. In its extreme advance position, the looper moves sidewise and begins to recede, the slack looper-thread thus produced being drawn in by the engagement of the thread intermediate the members 89 with the notches 87 of the cam-plates, until the inclined cast-off finger 94 forces the detained loop of looper-thread outwardly clear of the notches 87, when the 70 strain upon the looper-thread is entirely removed preparatory to the production of the succeeding stitch.

The crank-arm 60 upon the looper-actuating rock-shaft 18 has secured thereon by 75 means of screws 98 the foot 99 of a rearwardly extending pull-off arm 100 passing through a slot 101 in the head of the bracket-arm and adapted for vibratory movement between the spaced limbs of an arched 80 guide-member 102 formed with aligned thread-apertures 103 and provided with a foot-piece 104 secured by means of screws 105 to the head 4 of the bracket-arm. The 85 looper-thread passes from the source of supply through the tension device 106, thence through the apertures 103 of the guide-member 102, and through a guide-aperture 107 in the upper portion of the face-plate 5 to an aperture 108 in a flat nipper-spring 90 109 whose shank 110 is secured upon the outer side of the face-plate 5 by suitable means. As the thread emerges from the aperture 108 it rests against the forward face of the nipper-spring 109 and passes to 95 the guide-eye 95 of the looper-thread take-up device as before explained. Fixed upon the forward end portion of the looper-supporting rock-shaft 26 is a collar 111 formed with an upwardly projecting portion 112 to 100 which is secured by means of the screw 113 the arm 114 having an outwardly extending member 115 passing through an aperture 116 in the face-plate 5 and resting upon the adjacent face of the nipper-spring 109, and 105 thus affording a movable jaw for nipping the looper-thread between itself and the adjacent face of the spring 109. The member 115 is provided with a substantially V-shaped self-threading aperture 117 into 115 which the thread is readily introduced to insure its passage between the two jaws of the nipping device.

As the looper is moving to retracted position in a path in front of the needles, the 120 looper-supporting rock-shaft is in such position that the nipper member 115 is in operative or thread-clamping relation with the nipper-member 109, and the movement of the rock-shaft 18 in retracting the looper 125 raises the pull-off arm 100 so as to draw through the tension device 106 a supply of thread for the succeeding stitch, the retraction of the looper at the same time serving to draw up the looper-thread in the stitch 130.

1 just formed. As the looper performs its sidewise movement to the loop-seizing plane, the nipping device is opened, and the thread is allowed to pass freely between the tension and the take-up, which latter operates as 5 previously described in controlling the slack thread between the tension and the work.

10 Journaled in the base 1 beneath and transversely of the main-shaft 6 is a tension release rock-shaft 118 upon which is fixed the hub 119 carrying two angularly arranged arms 120 and 121 provided with wedge-shaped offset extremities 122 adapted to enter the space between the tension disks 15 70 and 71 to separate them for release of their pressure upon the needle-threads. The rock-shaft has upon its opposite end a crank-arm 123 through an aperture in which passes the pull-rod 124 with hooked upper end 125 20 engaging the presser-foot lifting rock-lever 126 in a manner well known. The two parts of the rod 124 are adjustably secured together by means of the coupling 127, the lower end of which engages the top of the 25 crank-arm 123 when the pull-rod is drawn downwardly to lift the presser-foot, thereby rocking the shaft 118 to open the needle-thread tension disks.

30 The machine is provided with a common form of feeding mechanism comprising the feed-dog 128 mounted upon the feed-bar 129 connected with the feed-rocker 130 actuated by suitable connections with the eccentric 131 upon the main-shaft, the feed-bar being 35 provided with a yoke 132 embracing the feed-lifting eccentric 133 upon the main-shaft adjacent the crank-plate 7.

30 The presser-bar 134 is suitably journaled in the head 4 of the bracket-arm and pressed 40 downwardly by means of the flat spring 135 and has secured to its reduced lower end, by means of the screw 136 the shank 137 of a compensating presser-foot formed with parallel vertical guideways to each of which is 45 fitted an upright arm 138 of one of the foot-plates 139 and 140 which are arranged side by side, the members 138 having rearwardly projecting pins 141 entering slots 142 in a rocking plate 143 fulcrumed upon the 50 presser-foot shank 137 by means of the stud-screw 144. The foot-plate 139 is the broader of the two and has at its inner edge the stitch-receiving tongue 145 separated from the body of the foot by the needle aperture 55 146, another needle aperture being afforded by the space 147 between said tongue and the adjacent edge of the other foot-plate 140. The stitch-receiving tongue 145 is made of wedge-shape by cutting away its top rearwardly in order to readily deliver the 60 stitches formed thereon, the needles rising through the forward extremities of the needle apertures and their threads being united by the looper-thread laid transversely 65 across the tongue 145 from which they are

drawn by the advance of the work under the action of the feeding mechanism.

As one of the chief objects of the present improvement is to provide means for uniting and covering the margin of a hem upon 70 the body fabric, requiring one needle to penetrate two plies and the other needle to penetrate a single ply of material, the compensating presser-foot just described is designed to coöperate with the stitching and 75 feeding mechanisms for such class of work. As the greater proportion of the composite seam is designed to overlie the margin of the upper ply of fabric, the presser-plate 139 which overlies the upper ply of material is 80 made considerably wider than the presser-plate 140 and the stitch-receiving tongue is made in the former so as to overlie the stitched edge of the fabric.

From the foregoing description, it will be 85 readily understood that the present improvement is susceptible of considerable modification of the construction and arrangement of its various parts within the scope of the invention, and that certain of 90 the features described may be modified or omitted without materially affecting the operation of the others.

Having thus set forth the nature of the invention, what I claim herein is:—

1. In a sewing machine, the combination with the frame comprising a base provided with needle-bar bearings and an overhanging bracket-arm, a main-shaft journaled in the base, a looper-actuating rock-shaft journaled in and extending longitudinally of the bracket-arm, and an operative connection between said shafts, of a reciprocating needle-bar journaled in said bearings and carrying a needle, a looper-supporting rock-shaft journaled in the bracket-arm; a looper mounted upon said supporting rock-shaft and adapted to oscillate upon an axis transverse thereto and to seize thread-loops from the needle, means connected with the looper-actuating rock-shaft for imparting to said looper its endwise operative movements, and means for rocking the looper-supporting rock-shaft to impart sidewise movements to the looper.

2. In a sewing machine, the combination with the frame comprising a base provided with needle-bar bearings and an overhanging bracket-arm, a main-shaft journaled in the base, a looper-actuating rock-shaft journaled in and extending longitudinally of the bracket-arm, and an operative connection between said shafts, of a reciprocating needle-bar journaled in said bearings and carrying a needle, a looper-supporting rock-shaft journaled in the bracket-arm, a looper mounted upon said supporting rock-shaft and adapted to oscillate upon an axis transverse thereto and to seize thread-loops from the needle, means connected with the looper-

actuating rock-shaft for imparting to said looper its endwise operative movements, and an operative connection between said looper-supporting rock-shaft and the main-shaft whereby sidewise movements are imparted to the looper.

3. In a sewing machine, the combination with the frame comprising a base provided with needle-bar bearings and an overhanging bracket-arm, a main-shaft journaled in the base, a looper-actuating rock-shaft journaled in and extending longitudinally of the bracket-arm, a looper-supporting rock-shaft also journaled in the bracket-arm parallel with the looper-actuating rock-shaft, and operative connections between the main-shaft and said rock-shafts, respectively, of a reciprocating needle-bar journaled in said bearings and carrying a needle, an operative connection between said needle-bar and the main-shaft, a normally stationary thread-guide adjustably mounted upon said base, a needle-thread take-up arm rigidly mounted upon the needle-bar and provided with a thread-guiding eye, a looper pivotally mounted upon the looper-supporting shaft, and an operative connection between said looper and the looper-actuating rock-shaft.

4. In a sewing machine, the combination with the frame comprising a base provided with needle-bar bearings and an overhanging bracket-arm, and a main-shaft, of a reciprocating needle-bar journaled in said bearings and carrying a needle, an operative connection between the main-shaft and said needle-bar, a loop-taker coöperating with the needle in the production of stitches and mounted for operative movement in the bracket-arm, and means acting while the needle is in the work for partially drawing up the needle-thread to reduce the loop offered by the needle to the loop-taker preparatory to the advance of the latter to seize a thread-loop.

45 5. In a sewing machine, the combination with the frame comprising a base provided with needle-bar bearings and an overhanging bracket-arm, and a main-shaft, of a reciprocating needle-bar journaled in said bearings and carrying a needle, an operative connection between the main-shaft and said needle-bar, a loop-taker coöperating with the needle in the production of stitches and mounted for operative movement in the bracket-arm, and thread-drawing means provided with actuating and controlling means acting intermediate the arrival of the needle at an extreme position and the adjacent loop-seizing position whereby it is caused to act upon the needle-thread twice while the needle is in the work and previous to seizure of a needle-thread loop by the loop-taker.

6. In a sewing machine, the combination with the throat-plate, of a plurality of upwardly directed reciprocating needles

adapted to carry loops of needle thread upwardly through said throat-plate, a loop-taker mounted above said throat-plate and adapted to coöperate with said needles in the production of stitches, actuating means for said needles and loop-taker, and thread-drawing means provided with actuating and controlling means acting during the recession of the needles from extreme position and prior to seizure of thread-loops therefrom by the loop-taker whereby it is caused to act differently in reducing the size of the loops thrown out by said needles for seizure by the loop-taker.

7. In a sewing machine, the combination with the frame comprising a base provided with needle-bar bearings and overhanging bracket-arm, and a main-shaft, of a reciprocating needle-bar journaled in said bearings, a plurality of needles mounted in said needle-bar, an operative connection between the main-shaft and said needle-bar, a loop-taker coöperating with said needles in the production of stitches and supported by the bracket-arm, actuating means for said loop-taker connected with the main-shaft, and thread-drawing means provided with actuating and controlling means acting during the recession of the needles from extreme position and prior to seizure of thread-loops therefrom by the loop-taker whereby it is caused to act differently in reducing the size of the loops thrown out by said needles for seizure by the loop-taker.

8. In a sewing machine, the combination with the main-shaft, of a reciprocating needle-bar carrying a needle, an operative connection between the main-shaft and said needle-bar, a loop-taker coöperating with the needle in the production of stitches, a needle-thread tension device, and thread-drawing means including a pivotally mounted thread-engaging element acting upon a portion of the needle-thread running freely from the tension device to the needle, said thread-drawing means being provided with actuating and controlling means whereby it is caused to act upon the needle-thread twice while the needle is in the work and previous to seizure of a needle-thread loop by the loop-taker.

9. In a sewing machine, the combination with the throat-plate, of a plurality of reciprocating needles adapted to carry loops of needle-thread through said throat-plate, a loop-taker adapted to coöperate with said needles in the production of stitches, actuating means for said needles and loop-taker, thread-drawing means comprising a plurality of coöperating thread-engaging elements movable relatively to each other and in correspondence with the reciprocatory movements of the needle, and actuating and controlling means acting immediately before seizure of each thread-loop by the loop-

- taker whereby the thread-engaging elements are caused to act differently in reducing the size of the loops thrown out by said needles for seizure by the loop-taker.
- 5 10. In a sewing machine, the combination with the throat-plate, of a reciprocating needle movable through said throat-plate, actuating means for said needle, a thread-carrying looper coöperating with said needle in the production of stitches, a looper-supporting rock-shaft carrying a transversely disposed fulcrum-pin upon which said looper is mounted, a looper-thread take-up also mounted upon the looper-supporting rock-shaft, means for actuating the looper-supporting rock-shaft, a looper-thread nipping member mounted upon a fixed support, a looper-thread nipping member carried by the looper-supporting rock-shaft and movable toward and from the fixed nipping member 50 for intermittently engaging the interposed looper-thread, and means for rocking said looper upon its fulcrum-pin.
- 10 11. In a sewing machine, the combination with the throat-plate, of a reciprocating needle movable through said throat-plate, actuating means for said needle, a thread-carrying looper coöperating with said needle in the production of stitches, a looper-supporting rock-shaft carrying a transversely 60 disposed fulcrum-pin upon which said looper is mounted, a looper-thread take-up also mounted upon the looper-supporting rock-shaft, means for actuating the looper-supporting rock-shaft, and means for rocking said looper upon its fulcrum with a frequency corresponding with that of the said movements imparted to the rock-shaft.
- 15 12. In a sewing machine, the combination with the throat-plate, of a reciprocating needle movable through said throat-plate, actuating means for said needle, a thread-carrying looper coöperating with said needle in the production of stitches, a looper-supporting rock-shaft carrying a transversely 65 disposed fulcrum-pin upon which said looper is mounted, a looper-thread take-up also mounted upon the looper-supporting rock-shaft, means for actuating the looper-supporting rock-shaft carrying a transversely 70 disposed fulcrum-pin upon which said looper is mounted, a looper-thread take-up also mounted upon the looper-supporting rock-shaft, means for actuating the looper-supporting rock-shaft, a looper-thread nipping member mounted upon a fixed support, a looper-thread nipping member carried by the looper-supporting rock-shaft and movable toward and from the fixed nipping member 75 for intermittently engaging the interposed looper-thread, a looper-thread tension device, a pair of spaced thread-eyes intermediate said tension device and the nipping device, a looper-thread pull-off arm fixed upon said looper-supporting rock-shaft and having a path of movement between said spaced thread-eyes, and means for rocking said looper upon its fulcrum-pin. 80
- 20 13. In a sewing machine, the combination with the throat-plate, of a reciprocating needle movable through said throat-plate, actuating means for said needle, a thread-carrying looper coöperating with said needle in the production of stitches, a looper-supporting rock-shaft carrying a transversely 85 disposed fulcrum-pin upon which said looper is mounted, a looper-thread take-up also mounted upon the looper-supporting rock-shaft, means for actuating the looper-supporting rock-shaft, a looper-thread nipping member mounted upon a fixed support, a looper-thread nipping member carried by the looper-supporting rock-shaft and movable toward and from the fixed nipping member for intermittently engaging the interposed looper-thread, a looper-thread tension device, a pair of spaced thread-eyes intermediate said tension device and the nipping device, a looper-thread pull-off arm fixed upon said looper-supporting rock-shaft and having a path of movement between said spaced thread-eyes, and means for rocking said looper upon its fulcrum-pin.
- 25 14. In a sewing machine, the combination with the throat-plate, of a reciprocating needle movable through said throat-plate, actuating means for said needle, a thread-carrying looper coöperating with said needle in the production of stitches, a looper-supporting rock-shaft carrying a transversely 90 disposed fulcrum-pin, a looper-carrier mounted upon said fulcrum-pin, a looper-thread engaging cam-plate fixed upon said looper-supporting rock-shaft and having operative edges in eccentric relation to said fulcrum-pin; a pair of thread-eyes embracing said cam-plate intermediate the operative edge of the same and said fulcrum-pin and sustained by said looper-carrier, actuating means for said looper-supporting rock-shaft, and means independent thereof for rocking said looper-carrier upon its fulcrum-pin.
- 30 15. In a sewing machine, the combination with the throat-plate, of a reciprocating needle movable through said throat-plate, actuating means for said needle, a thread-carrying looper coöperating with said needle in the production of stitches, a looper-supporting rock-shaft carrying a transversely 95 disposed fulcrum-pin, a looper-carrier mounted upon said fulcrum-pin, a looper-thread engaging cam-plate fixed upon said looper-supporting rock-shaft and having operative edges in eccentric relation to said fulcrum-pin; a pair of thread-eyes embracing said cam-plate intermediate the operative edge of the same and said fulcrum-pin and sustained by said looper-carrier, actuating means for said looper-supporting rock-shaft, and means independent thereof for rocking said looper-carrier upon its fulcrum-pin.
- 35 16. In a sewing machine, the combination with the throat-plate, of a reciprocating needle movable through said throat-plate, actuating means for said needle, a thread-carrying looper coöperating with said needle in the production of stitches, a looper-supporting rock-shaft carrying a transversely 100 disposed fulcrum-pin, a looper-carrier mounted upon said fulcrum-pin, a looper-thread engaging cam-plate fixed upon said looper-supporting rock-shaft and having operative edges in eccentric relation to said fulcrum-pin; a pair of thread-eyes embracing said cam-plate intermediate the operative edge of the same and said fulcrum-pin and sustained by said looper-carrier, actuating means for said looper-supporting rock-shaft, and means independent thereof for rocking said looper-carrier upon its fulcrum-pin.
- 40 17. In a sewing machine, the combination with the throat-plate, of a reciprocating needle movable through said throat-plate, actuating means for said needle, a thread-carrying looper coöperating with said needle in the production of stitches, a looper-supporting rock-shaft carrying a transversely 105 disposed fulcrum-pin, a looper-carrier mounted upon said fulcrum-pin, a looper-thread engaging cam-plate fixed upon said looper-supporting rock-shaft and having operative edges in eccentric relation to said fulcrum-pin; a pair of thread-eyes embracing said cam-plate intermediate the operative edge of the same and said fulcrum-pin and sustained by said looper-carrier, actuating means for said looper-supporting rock-shaft, and means independent thereof for rocking said looper-carrier upon its fulcrum-pin.
- 45 18. In a sewing machine, the combination with the throat-plate, of a reciprocating needle movable through said throat-plate, actuating means for said needle, a thread-carrying looper coöperating with said needle in the production of stitches, a looper-supporting rock-shaft carrying a transversely 110 disposed fulcrum-pin, a looper-carrier mounted upon said fulcrum-pin, a looper-thread engaging cam-plate fixed upon said looper-supporting rock-shaft and having operative edges in eccentric relation to said fulcrum-pin; a pair of thread-eyes embracing said cam-plate intermediate the operative edge of the same and said fulcrum-pin and sustained by said looper-carrier, actuating means for said looper-supporting rock-shaft, and means independent thereof for rocking said looper-carrier upon its fulcrum-pin.

In testimony whereof, I have signed my name to this specification, in the presence of two subscribing witnesses.

JOSEPH BERGER.
